UNITED STATES PATENT OFFICE.

GEORGE W. BERRY, OF ROSE BAY, NEAR SYDNEY, NEW SOUTH WALES, AUSTRALIA,
ASSIGNOR TO THE WIRELESS HINGE MANUFACTURING COMPANY LIMITED, OF
SYDNEY, NEW SOUTH WALES, AUSTRALIA.

DELIVERY MEANS FOR SHEET-METAL PRESSES.

1,311,588.

Specification of Letters Patent.

Patented July 29, 1919.

Application filed October 8, 1917. Serial No. 195,261.

To all whom it may concern:

Be it known that I, GEORGE WILLIAM BERRY, a subject of the King of Great Britain, residing in Rose Bay, near Sydney, in the State of New South Wales, Commonwealth of Australia, engineer, have invented new and useful Improvements in Delivery Means for Sheet-Metal Presses, of which the following is a specification.

10 This invention relates to improvements in and connected with sheet metal presses for forming hinge members on and hingedly connecting the lids and bodies of sheet metal receptacles and it has been devised particu-
15 larly in order to provide delivery means for sheet metal presses whereby connected lids and bodies can be correctly closed and discharged from the press.

The invention is directed to that class of 20 press which forms the subject-matter of my co-pending application for United States Letters Patent Serial No. 148,767 filed 15th February, 1917 and wherein three sets of dies are employed for simultaneously treat-
25 ing receptacle bodies and lids, means being furnished for progressively and intermittently passing lid and body blanks from one set of dies to another to form hinge members and connect the lids and bodies in three
30 successive operations.

The prior invention referred to comprises a cast metal frame wherein is mounted a base carrying three removable bottom dies and a reciprocatingly mounted die head carrying a 35 corresponding number of top dies. The top dies are adapted to move to and from and register with the bottom dies.

The lid and body blanks to be hingedly connected are fed to the machine through 40 chutes placed at one side thereof and are directed to the bottom dies along guideways by the intermittent operation of push rods reciprocatingly mounted in the top of the base.

45 When a lid and body have been advanced to a position opposite the first bottom die they are thrust over the back and front, respectively, thereof by push pads that are carried on bars reciprocatingly mounted on 50 the base. The top dies are timed to operate when the lids and bodies have been thrust

correctly on to the bottom dies to partially form the hinge members.

When the lid and body are raised clear of the forming members of the bottom die they 55 are moved outwardly by curved ejector arms and placed in advance of fingers on the push rods.

When a lid and body have been removed from the first bottom die they are carried 60 along the guideways to the second bottom die by the next inward stroke of the push rods. The lid and body are thrust on to the second bottom die by push pads operating in front and rear thereof and the operation of 65 the second set of dies completes the formation of the hinge members.

When the top dies commence to rise after completing the formation of the hinge members the body and lid are moved outwardly 70 from the second bottom die into the guideways by ejector arms.

The body and lid shaped by the second die are then moved opposite the front and back respectively of the third bottom die by the 75 next inward stroke of the push rods.

The body is thrust on to the front of the third bottom die by a push pad arranged and operating as before described. As the lid is carried forward opposite the rear of 80 the third die, it is placed in a holder which is adapted to carry it forward and place the pintles thereon correctly beneath the bulbed tongues on the back of the body.

When the third top die descends it closes 85 the bulbed tongues neatly over the pintles on the back of the rim lid thereby hingedly connecting the lid to the body.

When the top die recedes the lid holder commences to move outwardly and raises the 90 lid to a horizontal position. The body is removed from the bottom die by the action of a curved ejector arm simultaneously with the outward movement of the lid holder.

When the hinged lid and body are being 95 moved along from the back of the third bottom die by the next oncoming body the lid passes over an inclined bracket which is adapted to keep the lid in its raised position until it is passed within the sphere of 100 operation of a closing device located at the discharge end of the press.

Now the present invention has been devised in order to provide extremely simple and efficient means for facilitating the correct closing and discharging of hingedly connected lids and bodies from the machine.

In order that the invention may be readily understood reference will now be had to the accompanying sheets of explanatory drawings, wherein

10 Figure 1 is a view in perspective of a lid and a body blank of a receptacle.

Fig. 2 is a view in perspective of a lid and a body blank showing the hinge members formed thereon by the first and second 15 set of dies of the press.

Fig. 3 is a view in perspective showing the lid hingedly connected to the body of a receptacle and as removed from the third set of dies.

20 Fig. 4 is a view in sectional elevation of part of the press showing the closing device comprising the present invention applied thereto.

Fig. 5 is a view in plan of part of the 25 press showing the improvements applied thereto.

Fig. 6 is a view in side elevation of the 30 press fitted with the closing device constructed in accordance with the present invention.

In Figs. 4, 5 and 6 the press is shown in faint lines and the improvements are shown in heavy lines.

35 Figs. 7 and 8 are views in side elevation of the closing device drawn to a larger scale than Figs. 4, 5 and 6 and showing the parts thereof in their neutral and operative positions, respectively.

In the drawings like characters of reference 40 have been employed to indicate similar parts in the different views and the numerals 1 and 2 designate the lid and body blanks, respectively, of a receptacle. The hinge members of the lid comprise rolled pintles 3 and the hinge members of the body comprise bulbed tongues 4. The hinge members 3 and 4 of the lid and body are constructed as shown in Fig. 2 and are hingedly connected as shown in Fig. 3 of the drawings.

50 The frame 5 of the press is fitted with three bottom dies 6 and a reciprocatingly mounted die head 7 carrying three top dies 8. The guideways 9 for the lids and bodies are located in the front and rear of the bottom dies and the push pads 10 are arranged to force the lids and bodies from the guideways on to the bottom dies. The lids and bodies are removed from the bottom dies and returned to the guideways by means of 55 the ejector arms 11. The lids 1 are placed on the third bottom die by a holder 12 and when a hinged lid and body are passed along the guide-way toward the discharge end of the press the lid passes over an inclined bracket 13 which is adapted to keep the

said lid horizontal and clear the said third die and operative parts connected therewith. The hingedly connected lid and body after passing beyond the bracket 13 come within the sphere of operation of the closing device which forms the subject-matter of the present invention.

70 The closing device comprises a bifurcated bracket 14 which is bolted to the frame 5 in advance of the guideway 9 for the lids and fitted with two flat springs 15. The springs 15 are disposed and curved in such a way that the free edges of the lids will fall and rest thereupon when a hingedly connected lid and body are passed beyond the bracket 13. The springs 15 are just sufficiently strong to insure them supporting the hingedly connected lid in a horizontal or approximately horizontal position but not strong enough to offer sufficient resistance to cause 80 injury to the same when being closed on the body.

75 A spindle 16 passes transversely through the bifurcated bracket 14 and an arm 17 is fitted to the spindle in the bifurcation of the bracket. The upper end of the arm 17 is formed into a jaw 18 in which is pivoted the angle portion of a small bell-crank 19 having one arm projecting forwardly and the other arm projecting downwardly. The forwardly projecting arm of the bell-crank 19 is fitted with a spindle 20 carrying rollers 21 and the opposite arm of the bell-crank normally is kept thrust forwardly against a stop or abutment 22 by the action of a 85 spring 23.

90 The spring 23 is carried on a pin 24 fitted to and projecting rearwardly from the arm 17 and a nut or nuts 25 are fitted to the pin to adjust the pressure of the spring on the 95 depending arm of the bell-crank 19.

95 The outer end of the spindle 16 is fitted with a forwardly projecting and downwardly inclined arm 26 which is connected by an adjustable link or rod 27 to the upper end 110 of a lever 28, the lower end of which is pivoted to a stud 29 or the like on the side of the frame 5.

115 A roller 30 is mounted on the lever 28 about midway of its length and this roller is kept bearing against a cam 31 carried on a shaft 32 passing transversely through the rear of frame by a spring 33. One end of the spring 33 is connected to the lever 28 and the opposite end is connected to a stud 120 34 or the like on the side of the frame 5.

125 The guide-way 9 for the bodies extends beyond the third bottom die 6 in order to insure the bodies retaining their correct vertical positions while being directed to a discharge chute 35 fitted detachably to a bracket 36 fitted to the side of the frame 5.

130 When a hingedly connected receptacle is pushed clear of the inclined bracket 13 and the lid falls upon the springs 15 the lever

28 is timed to move rearwardly thereby causing the arm 17 to move forwardly and downwardly. The forward and downward movement of the arm 17 causes the rollers 5 21 on the bell-crank 19 to bear with a resilient pressure on the top of the lid and press it gently toward the body.

The downward pressure of the rollers 21 on the lid causes the springs 15 to be pressed 10 rearwardly from beneath the free edge of the lid thereby leaving the lid to close freely or to be pressed downwardly by the said rollers.

The closing device is operated during the 15 period when a lid and a body are being connected on the third bottom die and the said device is returned to its normal position prior to the said lid and body being moved within its sphere of operation.

20 The closing mechanism above described can be easily adjusted and obviates the distortion of the lid and body or the hinge connection therebetween when the receptacles are passing from the third set of dies to the 25 discharge chute. The discharge chute can be arranged horizontally or be inclined at any desired angle and delivers the hinged connected lids and bodies to a point required. Fitted to one side of the discharge 30 chute there may be a spring as 37—see Figs. 5 and 6—to insure the positive and complete closing of the lid over the body of the receptacle.

What I do claim is:—

- 35 1. In an apparatus for automatically forming and connecting hinge members on the lids and bodies of sheet metal receptacles the combination with a guideway for the bodies, of a bracket at one side of the 40 guideway, springs for supporting a lid approximately at right angles to a body in the guideway, an arm pivoted to and projecting upwardly from the bracket, a bell-crank pivoted to the arm, rollers on a forwardly 45 projecting arm of the bell-crank, a resilient connection between the opposite arm of the bell-crank and the pivoted arm, and means for imparting an oscillating movement to the pivoted arm.
- 50 2. In an apparatus for automatically forming and connecting hinge members on the lids and bodies of sheet metal receptacles, the combination of a guideway for the bodies, a bracket at one side of the guide-

way, a spring or springs on the bracket arranged to support a lid approximately at right angles to a body in the guideway, and a pivoted arm having rollers resiliently mounted thereon, constructed and arranged whereby when the pivoted arm is moved forward the rollers will be pressed upon the top of and close the lid against the body. 55 60

3. In an apparatus for automatically forming and connecting hinge members on the lids and bodies of sheet metal receptacles, a lid closing device comprising a bifurcated bracket, a pair of flat springs projecting forwardly and downwardly from the bracket, a spindle passing transversely through the bracket, an arm fitted to and 70 projecting upwardly from the spindle, a bell-crank pivoted to the free end of the arm, rollers on one arm of the bell-crank, a resilient connection between the opposite arm of the bell-crank and the arm on the 75 spindle, an arm fitted rigidly to and projecting forwardly and downwardly from the outer end of the spindle, a lever connected to the arm on the outer end of the spindle, and means for operating the lever. 80

4. In an apparatus for automatically forming and connecting hinge members on the lids and bodies of sheet metal receptacles, a lid closing device comprising in combination, a bracket, a spring or springs on 85 the bracket for supporting a lid approximately at right angles to a body, a spindle passing transversely through the bracket, an arm fitted rigidly to and projecting upwardly from the spindle, a bell-crank pivoted to the free end of the arm and having 90 one arm projecting forwardly and the other arm projecting downwardly, a spring exerting a forward thrust on the depending arm of the bell-crank, an arm fitted to and 95 projecting forwardly and downwardly from the outer end of the spindle, a link connecting the arm on the outer end of the spindle to a pivoted lever, a roller on the lever, a cam fitted to a shaft and bearing against the 100 roller, and a spring adapted to keep the roller bearing on the cam.

In testimony whereof I affix my signature in presence of two witnesses.

GEORGE W. BERRY.
